(57) **CLAIM**

The ornamental design for a display case, as shown and described.

DESCRIPTION

FIG. 1 is a left front perspective view of a display case showing the design of the present invention.

FIG. 2 is a front elevation view of a display case showing the design of the present invention; and,

FIG. 3 is a right side elevation view of a display case showing the design of the present invention.

The top, bottom, and rear views of the display case are not shown and form no part of the claimed design.

1 Claim, 3 Drawing Sheets
